MACHINE FOR PRESSING SHOE SOLES

Avedis Y. Chavoor, Worcester, Mass.

Application May 17, 1933, Serial No. 671,551

8 Claims. (Cl. 12—33)

This invention relates to a machine for use in cementing soles or half soles on shoes, particularly in connection with repair operations.

It is the object of my invention to provide a machine for such purposes by which a shoe and a cement-coated sole may be very quickly and conveniently placed under pressure and by which the pressure may be maintained for any desired period.

10 A further object of the invention is to provide a machine for such purposes so designed that it is readily adaptable for use on shoes of widely differing shapes and sizes and for either whole-sole or half-sole operations.

15 I have also provided improved devices for holding and supporting the shoe during the pressing operation.

20 My invention further relates to arrangements and combinations of parts which will be herein-after described and more particularly pointed out in the appended claims.

A preferred form of the invention is shown in the drawings, in which

25 Fig. 1 is a front elevation of my improved machine;

Fig. 2 is a sectional side elevation, taken along the line 2—2 in Fig. 1;

Fig. 3 is a sectional detail plan view, taken along the line 3—3 in Fig. 2;

30 Fig. 4 is an end elevation of the front shoe support, looking in the direction of the arrow 4 in Fig. 2;

Fig. 5 is a sectional elevation of certain detail parts;

35 Fig. 6 is a sectional side elevation showing parts of the machine in shoe-pressing position;

Fig. 7 is a detail sectional view, taken along the lines 7—7 in Fig. 4;

40 Fig. 8 is a bottom view of the back or heel support, looking in the direction of the arrow 8 in Fig. 2, and

Fig. 9 is a side elevation of the front shoe support.

45 Referring to the drawings, I have shown a duplex shoe pressing machine comprising a base 10, side frame members 11 and an upper frame member 12. The base 10 is recessed as indicated at 13 in Fig. 2 to conform generally to the longitudinal shape of a shoe bottom and to provide an air space underneath a rubber pad or cushion 14 which overlies the base 10 and covers the recess 13 therein.

50 The bottom of the recess is of the general outline of a shoe sole and a raised portion 13a at one end assists in locating the shoe by engaging

the heel thereof (Fig. 6). A depression 15 (Fig. 7) is also provided in the bottom of the recess 13 beneath each pressing device, said depression having the general outline of the sole of a shoe.

5 Each front shoe support 20 is pivoted at 21 to a bracket 22 slidable on a cross bar 23, which in turn is pivoted at 24 in a yoke 25 swiveled to the lower end of an adjusting screw 26 (Fig. 5) having a hand wheel 27 secured thereto. A heel support 28 is similarly slidable on the cross bar 23, and the bracket 22 and support 28 may each be secured in adjusted position by a clamping screw 29.

10 Each adjusting screw 26 is threaded into the lower end of a sleeve 30 which is slidable on a fixed rod or plunger 31, mounted in the upper frame member 12 and extending downward therefrom.

15 A bell crank or handle 32 is provided for each pressing device and is pivoted on a stud 33 mounted in bearings 34 on the under side of the top frame member 12. A pair of links 35 are pivoted at 36 to each handle 32 and are pivoted at 37 to each sleeve 30.

20 By swinging the handle 32 from the position shown at the right in Fig. 1 to the position shown at the left in Fig. 1, the shoe supports 20 and 28 are moved downward and a shoe mounted thereon is pressed against the cushion 14, which is thereby forced yieldingly downward into the recess 13 and against the recessed base member 10.

25 When the handle 32 is substantially in horizontal position, the lower portion of the handle and the associated links 35 act as toggle members to hold the shoe supports and shoe positively in the lowered position indicated in Fig. 6.

30 Each sleeve 30 is preferably provided with transverse openings 40 and each plunger 31 is provided with a corresponding transverse opening in which balls 41 are mounted and are pressed 40 yieldingly outward by a spring 42.

35 When a sleeve 30 is moved to raised position, the balls 41 enter the openings 40 in the sleeve 30 and releasably retain the sleeve and associated parts in raised position until the handle 32 is again swung forcibly downward.

40 The machine may be adapted for use on shoes of different lengths by sliding the bracket 22 along the cross bar 23 to a position where the shoe is suitably located longitudinally with respect to the recess 13 in the base 10, after which the back or heel support 28 is moved outward toward the dotted line position in Fig. 2 until the heel of the shoe is engaged thereby and firmly held against the front support 20.

The front support 20 may be adapted to shoes having different shaped toe portions by providing a separate toe piece 50 having a rib and slot connection to the front end of the support 20, so that one toe piece 50 may be removed and another toe piece of different outline may be substituted, such a substituted toe piece being indicated at 50a in Fig. 3.

The front shoe support 20 may also be made 10 in two parts 51 and 52 (Fig. 3), these parts being separable longitudinally and one part being provided with a lug or lateral projection 53 (Figs. 2 and 3) extending into a recess 54 in the other part and secured in adjusted position by 15 a clamping screw 55.

With this construction, the support 20 may be widened or narrowed to fit different shoes and the toe portion may be adapted to different shaped toes by using different toe pieces 50.

20 In the operation of my improved shoe pressing machine, the support 20 is adjusted to the particular size and type of shoe to be cemented, and the back or heel support 28 is adjusted to the right in Fig. 2 to firmly hold the shoe on the front support 28.

25 It will be noted that the support 28 has a forwardly extended portion 60 overlapping a rearwardly extended portion 61 of the support 20. This overlapping feature permits a much wider range of relative adjustment of the back support 28 and also provides a sufficiently continuous surface for the shank portion of the shoe.

For half-sole operations, the front support 20 may be used alone as indicated in Fig. 9, the back 30 support 28 being removed. By adjusting the screw 25 in the lower end of the sleeve 30, any desired final pressure may be secured.

When the shoe is in the pressing position indicated in Fig. 6, the rubber cushion 14 snugly engages the shoe sole or half-sole at all exterior portions thereof and forces the same firmly against the sole of the shoe, in which position the sole is retained during the drying and setting of the cement.

40 The sole-shaped depressions 15 in the bottom of the recess 13 substantially assist the operation by providing exceptionally heavy pressure around the edge portions of the sole where firm contact and a tight joint is particularly essential.

50 An important advantage of my improved pressing machine lies in the fact that no last is used and that no pressure is applied to the shoe upper at any point, as has been the custom in machines previously used for this purpose. The application of pressure to the shoe upper quite commonly results in injury to the shoe, particularly to ladies' shoes formed of light or easily defaced materials.

55 In the operation of cementing soles to shoes, particularly for repair purposes, it is necessary to place the cemented parts under pressure with the least possible delay if a firm and tight joint is to be attained. Reference to the drawings will show that my improved machine is particularly adapted for such rapid operation, as the front shoe support 20 may be adjusted in position before the shoe parts are cemented and the adjustment of the heel support 28 and downward movement of the lever 32 may be performed almost simultaneously and with great rapidity.

60 While I have shown my improved machine in duplex form, so that a pair of shoes may be conveniently cemented and pressed at the same time, it will be obvious that a single pressing device may be made embodying my improvements.

Having thus described my invention and the advantages thereof, I do not wish to be limited to the details herein disclosed, otherwise than as set forth in the claims, but what I claim is:—

5 1. In a machine for pressing shoe soles, in combination, a frame having a top member, a rod fixed in said top member and extending downward therefrom, a sleeve vertically slidable on said rod, means to move said sleeve vertically and to lock said sleeve in lowered position, a cross bar pivotally connected to the lower end of said sleeve, front and back shoe supports slidable on said cross bar, means to secure said supports in adjusted position on said cross bar, and a cushioned form to receive the downward pressure of 10 15 the shoe mounted on said supports.

2. In a machine for pressing shoe soles, in combination, a vertically movable member, a cross bar pivoted thereto on an axis transverse of said bar, a bracket slidable thereon, means to secure 20 said bracket in adjusted position, and a front sole-engaging shoe support pivoted to said bracket.

3. In a machine for pressing shoe soles, in combination, a vertically movable member, a cross 25 bar pivoted thereto on an axis transverse of said bar, front and back sole-engaging shoe supports mounted to slide relative to said cross bar, and means to secure said supports in adjusted position.

30 4. In a machine for pressing shoe soles, in combination, a vertically movable member, a cross bar mounted thereon, front and back shoe supports mounted to slide relative to said cross bar, and means to secure said supports in adjusted 35 position, said supports having overlapping portions permitting extended relative longitudinal adjustment while maintaining engagement thereof.

40 5. In a machine for pressing shoe soles, in combination, a vertically movable member, a cross bar mounted thereon, a bracket slidable thereon, means to secure said bracket in adjusted position, and a front sole-engaging shoe support pivoted to said bracket, said front shoe support 45 being formed in longitudinally divided parts, and means being provided for securing said parts in selected spaced relation.

6. In a machine for pressing shoe soles, in combination, a vertically movable member, a cross 50 bar pivoted thereto, a bracket slidable thereon, means to secure said bracket in adjusted position, and a front sole-engaging shoe support pivoted to said bracket, said front shoe support having a removable and replaceable toe piece detachably mounted at the front end thereof.

55 7. In a machine for pressing shoe soles, in combination, a vertically movable member, a cross bar pivoted thereto, a bracket slidable thereon, means to secure said bracket in adjusted position, and a front sole-engaging shoe support pivoted to said bracket, said front shoe support having a removable and replaceable toe piece detachably mounted at the front end thereof and having a rib and slot connection thereto.

65 8. In a machine for pressing shoe soles, in combination, a vertically movable member, a cross bar pivoted thereto, a bracket slidable thereon, means to secure said bracket in adjusted position, and a front shoe support pivoted to said bracket, said shoe support being shaped to substantially conform to the front and shank portions of a shoe mounted thereon.
